(57) **CLAIM**

The ornamental design for a putter head, as shown and described.

DESCRIPTION

FIG. 1 is a perspective view of the putter head;

FIG. 2 is a top view of the putter head;

FIG. 3 is a bottom view of the putter head;

FIG. 4 is a side view of the putter head;

FIG. 5 is a rear view of the putter head; and,

FIG. 6 is a front view of the putter head.

The broken lines showing in the figures are included for the purpose of illustrating portions of the putter head that form no part of the claimed design. The dash-dot lines showing in the figures are included for defining the bounds of the claimed design that form no part thereof.
